UNITED STATES PATENT OFFICE.

JAMES A. DAVIESS, OF CHICAGO, ILLINOIS, ASSIGNOR TO AMERICAN STEAM CONVEYOR CORPORATION, OF CHICAGO, ILLINOIS, A CORPORATION OF NEW YORK.

ASH-CONVEYER SYSTEM.

1,293,360.

Specification of Letters Patent.

Patented Feb. 4, 1919.

Application filed March 24, 1917. Serial No. 157,139.

To all whom it may concern:

Be it known that I, JAMES A. DAVIESS, a citizen of the United States, residing at Chicago, in the county of Cook and State of Illinois, have invented a certain new and useful Improvement in Ash-Conveyer Systems, of which the following is a full, clear, concise, and exact description, reference being had to the accompanying drawings, forming a part of this specification.

This invention relates to ash conveyer systems and broadly stated is concerned with the provision of means associated with the pipe line of such a system arranged to permit the removal, replacement, and substitution of portions of the pipe line which in the operation of the system become excessively worn due to the abrasive action of the ashes conducted therethrough, without materially disturbing the system or the line of pipe or conduit in which said portions are found.

Conveying systems of the class to which my present invention relates comprise metal conduits or pipes through which the ashes are conducted or moved by suction or draft of air created by steam jets or suitable blower or fan mechanism. While I prefer to employ my invention in connection with an ash conveyer of the steam jet type it is equally applicable to other systems.

In conveying systems of the class under consideration it often, in fact ordinarily, is necessary to provide both horizontal and vertical pipe lines and even oblique runs of pipe, wherefore it is very difficult to avoid the use of elbows or at any rate more or less abrupt bends or turns in the pipe lines. As is generally known to persons familiar with this class of conveyer systems the presence of abrupt bends or turns in the pipe line is accompanied by an excessive or unequal degree of wear at such points as a result of the abnormal abrasive action of the ashes at the point where the direction of flow thereof is abruptly changed or altered. It has been the practice in the past because of this excessive wear at the bends to provide elbows comprising removable sections or provided with removable wear liners or backs. It has been found, however, that the excessive

abrasive action of the ashes occasioned by an abrupt change of the direction in the pipe line is not confined to the elbow or curved portion of the pipe but extends through the straight portion of the pipe for a considerable distance beyond the elbow in the direction of flow. This is probably accounted for by the fact that the ashes after leaving the elbow or curved portion of the pipe line do not immediately resume their normal flow along the axis of the pipe but are for some distance carried along in more or less violent contact with the inner surface of the pipe.

In order to provide for the wear which occurs just beyond the elbow or bend as just explained, the use of a short section or length of pipe that may be removed and renewed from time to time has been suggested. However, it is ordinarily no simple matter to remove such a pipe section from the other elements of the pipe line and this is particularly true when the removable pipe length is located in a vertical riser extending upwardly from a horizontal pipe line with which it is connected by an elbow or other curved pipe fittings. Heretofore in such a case the entire weight of the vertically disposed pipe line has been carried upon the removable pipe length and elbow with the result that in order to remove the elbow or the aforesaid short length of pipe or to shift the position of the latter with respect to its associated pipe sections has necessitated the provision of special equipment of various kinds for temporarily supporting those elements of the conduit above the sections thereof that are to be removed, replaced, or shifted.

The object of my present invention is to provide simple and inexpensive means having a two-fold function, firstly, to afford a vertical conduit riser such longitudinal and lateral support as it requires, and, secondly, to support the upper sections of such a riser independently of a removable wear section or sections therebeneath, in order that the latter may be readily removed, replaced, or shifted with respect to the permanent conduit sections as conditions require.

My invention is fully set forth in the de-

scription to follow, wherein reference is made to the accompanying drawings, in which—

Figure 1 is a view in end elevation of a portion of a steam jet ash conveyer system equipped with the devices of my present invention;

Fig. 2 is a side elevational view of the same;

Fig. 3 is a horizontal sectional view taken on the line 3—3 of Fig. 1;

Fig. 4 is a vertical sectional view taken on the line 4—4 of Fig. 3, and

Fig. 5 is a fragmentary view partly in section and partly in elevation of certain parts of an ash conveyer system equipped with the devices of my invention.

Similar characters of reference refer to similar parts throughout the several views.

Referring first to Figs. 1, 2 and 5, it will be noted that the ash conveyer system comprises cast iron pipes of suitable capacity, the abutting sections of which are provided with cooperating flanges secured together in any well known manner, as by bolts passing through registering apertures or slots in the coöperating flanges.

The system herein shown comprises a horizontal run of pipe comprising a plurality of sections 10—10, one of which is shown in Fig. 2. As is usually the case, the horizontal run of pipe is disposed in a trough or tunnel with the horizontal pipe sections 10—10 resting upon the tunnel floor 11 as shown.

The horizontally disposed portion of the conveyer conduit communicates with a vertical riser and I prefer to afford this communication through a long radius elbow comprising sections 12, 13, 14 and 15, although

my invention contemplates the use of any other form of elbow that may prove desirable or expedient. The system being of the steam jet type, I prefer to provide the elbow section 15 with a steam supply pipe 16 which communicates with a nozzle (not shown) carried by the section 15 and discharging upwardly into the conduit.

The vertical riser comprises a removable pipe length 17 and as many sections 18 as conditions require, it being understood that in the normal operation of the system the ashes are carried along in the horizontal run of the conduit toward the long radius elbow and out through the vertical riser and other conduit elements (not shown) to a suitable discharge point. As my present invention is concerned with the provision of means for supporting and permitting the removal, replacement, and adjustment of certain parts of the system shown in the accompanying drawings, it will be unnecessary for me to illustrate or describe other parts of the system, as the same are well known to those familiar with the art to which the

invention relates.

In the operation of the system the change in the direction of the flow of the ashes when the latter passes through the long radius elbow sections up into the vertical riser subjects not only the elbow sections but also the straight pipe section 17 beyond the elbow to more or less wear with the result that it is frequently desirable to remove and inspect said removable section 17, re-adjust its position with respect to the conduit elements 15 and 18 or substitute another removable section therefor. Heretofore the pipe sections 18 and other conduit elements with which it connects have been supported by the section 17 and the elbow sections, with the result that when it has been necessary to remove the straight section 17 or one of the elbow sections, special and elaborate means has been required to support the elements of the riser, so that the parts which have been worn may be removed. My invention contemplates the provision of means constituting a permanent part of the system which contributes the required support to the conduit sections above the pipe length 17 and elbow and which carries the parts above the removable pipe length 17 independently of the elbow and pipe length 17 when the pipe length 17 or elbow or any section of the latter is to be removed.

The means for accomplishing the purpose just mentioned comprises a yoke or clamp arranged to embrace the first conduit section above the removable pipe length 17. Said yoke or clamp comprises a pair of strap metal members 19—19, each of which is conformed intermediate its ends to receive the cylindrical surface of the conduit section 18. The corresponding ends of the yoke members 19—19 are brought together, as is most clearly illustrated in Fig. 3, by bolts 20—20 and 20^a—20^a, the bolts 20 and 20^a of each pair being spaced apart to receive between them one of the head pieces of a supporting standard presently to be described.

Disposed upon the floor 11 and situated on opposite sides of the conduit adjacent the elbow are the standard bases 21—21, each of which is in the form of an integral casting conformed to provide a cylindrical upwardly projecting boss 21^a and an annular recess 21^b. The adjustable standard of which each base member 21 forms a part comprises a tubular element 22 which may be a length of standard gas pipe having its lower end disposed around the boss 21^a and disposed in the annular recess 21^b of the base.

Disposed above each of the tubular elements 22 and in axial alinement therewith is a second tubular element 23 which at its upper end carries a head piece 24. Each of the head pieces 24—24 consists of an integral casting comprising a cylindrical boss 24^a received by the upper end of its associated tubular element 23 and an annular re-

cess 24^b in which the upper end of said tubular element engages. Formed in the upper portion of each of the head pieces 24—24 is a transverse slot 24^c which adapts the head to embrace the connected ends of the yoke or clamp members 19—19 intermediate the bolts 20 and 20^a, whereby said ends of the clamp members are secured together.

Interposed between the tubular elements 10 22 and 23 of each standard is a bolt 25 having its ends screw threaded in opposite directions, one end of said bolt being freely disposed within the upper end of the lower tubular element 22 and its upper end freely disposed within the lower end of the tubular element 23. Threaded upon the bolt 25 of each standard are the nuts 26—26, the washers 27—27 being interposed between said nuts and the lower and upper tubular 20 elements as shown. It will thus be seen that adjustment of the nuts 26—26 with respect to the bolts 25 changes the effective length of the latter and thereby varies the height of the standard heads 24—24.

25 The vertical standards just described normally contribute to the support of the conduit riser and hold it against lateral displacement. Whenever it becomes necessary or desirable to remove the conduit length 17 30 or any one of the elbow sections, these being the parts which are subjected to the most excessive wear, the nuts 26—26 are adjusted to increase the effective length of the bolts 25—25, thereby lifting the standard heads 35 24—24 and taking all of the weight of the conduit section 18 and parts thereabove off of the worn sections, whereby the latter may be removed, inspected, readjusted or replaced with ease and without deranging the 40 other parts of the system.

It will be understood that the pipe section 17 may be either standard pipe or that its walls may be of greater cross section than the other pipes constituting the conduit to 45 compensate for the excessive wear to which the pipe 17 is subjected in the normal operation of the system.

It will thus be seen that I have provided simple and inexpensive means for spacing 50 the permanent elements of a conduit riser from the worn parts when said worn parts are to be renewed and for supporting the former independently of the latter, wherefore it is possible to remove and replace the 55 worn parts without deranging the permanent elements of the conduit.

While I have described my invention as applied to the conduit of a conveyer of the steam jet type, it will be understood that my 60 invention is not so limited but may be applied to various types of material conveyers.

What I claim as new and desire to secure by Letters Patent of the United States, is:

1. In a system for conveying ashes or the 65 like the combination of two pipe sections,

a removable pipe section interposed between said first mentioned sections, and a device for supporting one of said first mentioned pipe sections independently of the other together with means for varying the 70 distance between the ends of said first mentioned pipe sections.

2. In a system for conveying ashes and the like, a riser comprising two pipe sections, a removable pipe section insertible between the ends of and normally held against longitudinal movement by the first mentioned pipe sections, and means for supporting the upper one of said first mentioned pipe sections independently of the pipe sections therebeneath. 80

3. In a system for conveying ashes and the like, a riser comprising two pipe sections, a removable pipe section insertible between the ends of the first mentioned pipe sections 85 and means capable of longitudinal adjustment for supporting the upper one of said first mentioned pipe sections independently of the removable pipe section and the other of said first mentioned pipe sections. 90

4. In an ash conveyer system, a riser comprising pipe sections, a removable wear section interposed between said pipe sections and a longitudinally adjustable standard extending from a fixed support for supporting the upper one of said pipe sections independently of the removable wear section. 95

5. In an ash conveyer system, the combination with a horizontal conduit extending over a fixed support, a riser, an elbow affording communication between the horizontal conduit and said riser, said riser comprising a removable wear section, and means extending from said fixed support for supporting that part of the riser above the removable wear section independently of the latter. 100

6. In an ash conveyer system, a riser, a removable pipe section constituting a part of said riser, pipe sections above and below 110 said removable pipe section, a yoke encircling the upper one of said last mentioned pipe sections and a pair of standards extending from a fixed support arranged to carry said yoke and thereby that part of 115 the riser above said removable pipe section.

7. In an ash conveyer system, a riser, a removable pipe section constituting a part of said riser, pipe sections above and below 120 said removable pipe sections, a yoke encircling the upper one of said last mentioned pipe sections and a pair of longitudinally adjustable standards extending from a fixed support arranged to carry said yoke and thereby that part of the riser above said removable pipe section. 125

8. In an ash conveyer system, a riser, a removable pipe section constituting a part of said riser, pipe sections above and below 130 said first mentioned pipe section, a yoke en-

circling the upper one of said last mentioned pipe sections, said yoke comprising a pair of bands encircling said pipe sections and having their ends brought together on opposite sides thereof, and a pair of standards extending from a fixed support having their upper ends conformed to receive the ends of said yoke bands, whereby to carry the yoke and thereby that portion of the 10 riser located above said removable pipe section.

9. In an ash conveyer system, a riser, a removable pipe section constituting a part of said riser, pipe sections above and below 15 said first mentioned pipe section, a yoke encircling the upper one of said last mentioned pipe sections, said yoke comprising a pair of bands encircling said pipe sections and having their ends brought together on opposite sides thereof, and a pair of standards extending from a fixed support having their upper ends conformed to receive the ends of said yoke bands, whereby to carry the yoke and thereby that portion of the 20 riser located above said removable pipe section, each of said standards comprising two 25 pipe sections disposed in axial alinement with their contiguous ends freely receiving

the ends of a bolt, and nuts coöperating with said bolts, whereby the effective length 30 of said standards may be varied as desired.

10. In an ash conveyer system of the class described, the combination with horizontal and vertical conduits, an elbow affording communication between said horizontal and 35 vertical conduits, and means capable of longitudinal adjustment for supporting said vertical conduit independently of said elbow.

11. In a pipe conveying system, the combination with two pipe sections of a removable pipe section interposed between said first named sections, and forming an airtight connection therewith, and means for supporting one of said first-mentioned pipe 45 sections independently of the other, together with means for varying the distance between the ends of said first-mentioned pipe sections.

In witness whereof, I hereunto subscribe 50 my name this 21st day of March, A. D. 1917.

JAMES A. DAVIESS.
